US00D457887S

(12) **United States Design Patent** (10) Patent No.: **US D457,887 S**
(45) Date of Patent: **** May 28, 2002**

(54) **RECORDING MEDIUM**

(75) Inventor: **Akira Kadonaga**, Tokyo (JP)

(73) Assignee: **Sony Corporation**, Tokyo (JP)

(**) Term: **14 Years**

(21) Appl. No.: **29/148,785**

(22) Filed: **Sep. 28, 2001**

(51) LOC (7) Cl. **14-02**

(52) U.S. Cl. **D14/436; D13/182**

(58) Field of Search **D14/435-438, D14/478, 480, 479, 474; D13/182; 174/16,3, 52.1, 52.2, 52.4; 257/670, 676, 686, 688, 690, 691, 692, 696, 703, 787; 437/217; 361/679, 736, 737, 742, 752; 235/492, 441; 439/353, 60, 633, 677**
